US00D978942S

(12) **United States Design Patent** (10) Patent No.: **US D978,942 S**
(45) Date of Patent: **** Feb. 21, 2023**

(54) **INTELLIGENT SERVICE ROBOT**

(71) Applicant: **Robotise AG**, Munich (DE)

(72) Inventors: **Johannes Fuchs**, Munich (DE); **Oliver Stahl**, Munich (DE)

(73) Assignee: **ROBOTISE AG**, Munich (DE)

(**) Term: **15 Years**

(21) Appl. No.: **29/758,319**

(22) Filed: **Nov. 13, 2020**

(30) **Foreign Application Priority Data**

May 14, 2020 (WO) WIPO94894

(51) LOC (14) Cl. **15-99**

(52) U.S. Cl.

USPC **D15/199**

(58) **Field of Classification Search**

USPC D15/199; D21/369, 578-583, 622; D24/137-140, 146, 150, 232

CPC A63H 11/00; B25J 9/0003; Y10S 901/01

(57) **CLAIM**

The ornamental design for an intelligent service robot, as shown and described.

DESCRIPTION

FIG. 1 is a rear view of a first embodiment of an intelligent service robot showing a first embodiment of our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a rear view of a second embodiment of an intelligent service robot showing a second embodiment of our new design;

FIG. 9 is a front view thereof;

FIG. 10 is a left side view thereof;

FIG. 11 is a right side view thereof;

FIG. 12 is a top view thereof;

FIG. 13 is a bottom view thereof; and,

FIG. 14 is a perspective view thereof.

The broken lines in FIG. 13 show portions of an intelligent service robot which form no part of the claimed design.

The light grey areas in FIG. 6 show portions of an intelligent service robot which form no part of the claimed design.

1 Claim, 12 Drawing Sheets
